UNITED STATES PATENT OFFICE.

NILS D. LEVIN, OF COLUMBUS, OHIO, ASSIGNOR TO THE JEFFREY MANUFACTURING COMPANY, OF COLUMBUS, OHIO, A CORPORATION OF OHIO.

AXLE JOURNAL-BOX FOR OUTSIDE-WHEEL LOCOMOTIVES.

1,273,884.

Specification of Letters Patent. Patented July 30, 1918.

Application filed February 20, 1915, Serial No. 9,744. Renewed October 27, 1917. Serial No. 198,883.

To all whom it may concern:

Be it known that I, NILS D. LEVIN, a citizen of the United States, residing at Columbus, in the county of Franklin and 5 State of Ohio, have invented certain new and useful Improvements in Axle Journal-Boxes for Outside-Wheel Locomotives, of which the following is a specification, reference being had therein to the accompanying 10 drawing.

This invention relates to improved devices for connecting the truck frames of cars or locomotives to the axles and track wheels upon which they are mounted, and particularly to devices for mounting or supporting the power-receiving axles in small locomotives such as are used in mines. In some cases the conditions are such that the wheels can be located outside of the axle 15 boxes. In others, they must be located so that the journal parts of the axles will be situated outside of the wheels, as shown in my application Serial No. 853,770, filed July 28, 1914. When the wheels are located 20 outside of the journal boxes, I have found that provision must be made for taking the end thrust of the axles to the rigid parts of the truck frame, and means for accomplishing this are herein illustrated and described.

30 Of the drawings,

Figure 1 is a side elevation of a locomotive provided with my improved journal boxes.

Fig. 2 is a fragmentary horizontal sectional view taken along the line 2—2 of Fig. 1.

Fig. 3 is a fragmentary vertical sectional view taken along the line 3—3 of Fig. 1.

Fig. 4 is a fragmentary vertical sectional 40 view taken along the line 4—4 of Fig. 3.

Referring to the drawings, 1 represents one of the outer side walls or plates forming one of the main elements of the locomotive. This is shown as a single sheet of rolled 45 metal, this being the construction preferred. This plate 1 is formed with apertures of suitable size or with wide slots or notches which extend upward from the bottom. These notches or apertures are adapted to 50 receive the journal boxes and the axles.

2, 2 are frame and spacing bars arranged vertically at the edges of each aperture and on the inside of the truck plate 1. To the

inner faces of these are secured the vertical plates 3, with their inner edges projecting 55 somewhat beyond the bars 2 to provide guides for the axle box.

At the bottom of the aperture a cross bar 6 is arranged which stiffens the frame, holds the two side edges in the proper plane, and 60 prevents displacement of the journal box, the latter being particularly liable to occur in case the locomotive is derailed.

The journal box is indicated at 5. It is formed with an upper part 5^a, a lower part 65 5^b and connecting side parts; and in the latter there are formed grooves 4 which fit the guide edges of the plates 3, the box being allowed a vertical play relative to the truck body. 7, 7 are upwardly opening sockets 70 formed in the upper part of the box, and in these are seated the spring 8. 9 is a bar, which is rigidly riveted to the truck plate 1, the horizontal part of the angle being near the planes of the upper edge of the aperture 75 in the side wall and bearing downward upon the tops of these springs. 10 indicates the bearing piece or bushing, customarily made of brass, and arranged to rest and bear upon the journal part 11 of the axle 11^a. The 80 weight of the truck part of the locomotive or cars bears downward through the parts at 9, 8, 5 and 11 upon the wheel 12, and this in turn on the rails 13. It will be observed that the wheel 12 is secured to the 85 axle at a point outside of the frame, the construction in this respect being different from that in my copending application above referred to.

An oil hole 5^c is provided in each box 5, 90 this communicating with an oil groove in the bearing piece 10. Surplus oil can accumulate in the chamber in the lower part of the box.

A socket is formed in the end of the axle 95 11 and into this there is tightly fitted a thrust element 15 which is preferably a hardened steel pin driven into an aperture formed in the shaft at its axis. An opposing thrust element 16 is provided and suitable means are provided for supporting this in position to coöperate with the element 15. The supporting means shown is a longitudinal bar 17 which extends substantially from one end of the locomotive to the 100 other past both of the axles. This can be

supported in any desired way, and I have found that it can, in many cases, be conveniently supported, as shown, upon the boxes 18 which also serve as reservoirs for sand. The thrust member 16 is preferably a hardened steel plate tightly fitted into a seat in the bar. It can be fastened in any suitable way, as, for instance, by upsetting the end 16^a.

10 It will be observed that these thrust taking parts 15 and 16 are so shaped, arranged and related that the endwise thrust of the axle is taken at points directly at or adjacent to its axis.

15 There are many sets of conditions under which it is desirable to have the track wheels outside of the frame. One reason for this arrangement is the frequent desirability of keeping the overhaul width of the locomotive as small as possible. It will readily be seen that the placing of the necessarily large axle boxes outside of the wheels materially increases the total width of the locomotive. But with the construction shown the large 20 axle boxes are on the inside and do not increase the width. For taking the end thrust of the axles I have provided a simple means which is outside of the wheels but which does not materially increase the width 25 of the locomotive. This means comprises the bars 17 and the thrust plates 16 which engage the pins 15. By this construction I have not only provided a thrust means which does not materially increase the width of 30 the locomotive, but I have also provided one which is extremely simple in construction and is capable of being easily renewed in case of wear.

As stated, the parts 15 and 16 can be 35 constructed of hardened steel and their position is such that no material can accumulate between their surfaces. In order to make renewal easily possible the parts are mounted in more or less exposed positions, 40 but any grit which may fall on these parts will at once fall from them. And if it is noticed at any time that excessive wear has occurred the bars 17 can be removed and the parts 15 and 16 taken out and replaced. It 45 will be obvious that the bearing plate 16 can be easily removed from the bar by striking it at the end 16^a. One way for accomplishing the removal of the pin 15 is to form a few turns of an external thread at the outer 50 end of the pin prior to inserting it, and then, when the pin is to be withdrawn, rotating a suitable nut upon this threaded end which will quickly draw it loose.

I do not herein claim any of the subject 55 matter for which claims appear in my earlier application No. 853770, filed July 28, 1914; the claims herein relating more particularly to the form and arrangement of thrust elements when combined with wheels of the 60 class of that herein; I preferring to claim in

said earlier application the novel features of construction which are common to both mechanisms.

What I claim is:

1. In a mechanism for mounting and holding a car axle, the combination of a journal box engaging with the journal part of the axle, a frame element carried by the journal box, a track wheel rigidly secured to the axle outside of the journal box, a thrust element removably connected to the axle at its end, a second thrust element positioned outside of the said wheel, the said thrust elements being arranged to contact with each other at points which are proximate to the axis of the axle, and means supplemental to the axle and to the first said thrust element for holding the second said thrust element against movement longitudinally of the axis of the axle. 80

2. In a mechanism for mounting and holding a car axle, the combination of a journal box engaging with the journal part of the axle, a frame element carried by the journal box, a track wheel rigidly secured to the axle outside of the journal box, a thrust element removably connected to the axle at its end, a second thrust element positioned outside of the said wheel, the said thrust elements being arranged to contact with each other at points which are proximate to the axis of the axle, and means supplemental to the axle and to the first said thrust element for holding the second said thrust element rigidly to the said frame 90 element. 95

3. In a mechanism for mounting and holding a car axle, the combination of a journal box engaging with the journal part of the axle, a frame element resiliently carried by the journal box and vertically movable relatively thereto, a track wheel rigidly secured to the axle outside of the journal box, a thrust element removably connected to the axle at its end, a second thrust element positioned outside of the said wheel, the said thrust elements being arranged to contact with each other at points which are proximate to the axis of the axle, and means supplemental to the axle and to the first 105 said thrust element for connecting the second said thrust element rigidly to the said frame 110 element. 115

4. In a mechanism for mounting and holding a car axle, the combination of a journal box engaging with the journal part of the axle, a frame element carried by the journal box, a track wheel secured to the axle outside of the journal box, a thrust element removably connected to the axle at its 120 end, a second thrust element positioned outside of the said wheel, the said thrust elements being arranged to contact with each other at points which are proximate to the axis of the axle and the space below the 125 130

said elements being unobstructed to permit the free discharge of foreign material, and means supplemental to the axle and to the first said thrust element for connecting the 5 second said thrust element rigidly to the said frame element.

5. The combination of a car frame, two axles extending transversely of the frame, track wheels rigidly secured to the axles 10 outside of the frame, journal boxes engaging with the journal parts of the axles inside of the wheels, longitudinal bars secured to the frame outside of the wheels adjacent the ends of the axles and means serving to hold the axles against longitudinal movement.

6. The combination of a car frame, two axles extending transversely of the frame, track wheels rigidly secured to the axles 20 outside of the frame, journal boxes engaging with the journal parts of the axles inside of the wheels, thrust elements connected to the axles at their ends, two longitudinal bars secured to the frame outside of the wheels

adjacent the ends of the axles, and means 25 serving to hold the axles against longitudinal movement in either direction.

7. The combination of a car frame, two axles extending transversely of the frame, track wheels rigidly secured to the axles 30 outside of the frame, journal boxes engaging with the journal parts of the axles inside of the wheels, thrust elements connected to the axles at their ends, longitudinal bars 35 outside of the wheels adjacent the ends of the axles, and second thrust elements carried by the bars and thereby held stationary longitudinally of the axle, said thrust elements being arranged to contact with each other at points which are proximate to the 40 axes of the axles.

In testimony whereof, I affix my signature, in presence of two witnesses.

NILS D. LEVIN.
